ROTARY HYDRAULIC MOTOR OR PUMP

Gunnar A. Wahlmark, Rockford, Ill.

Application May 17, 1937, Serial No. 143,070

10 Claims. (Cl. 74—60)

The invention relates to a fluid motor or pump and it is a general object of the invention to provide a new and improved device of that character.

5 A more particular object of the invention is the provision in a device of that character having reciprocatory fluid handling mechanism and a rotatably mounted shaft of new and improved conversion mechanism for transforming the reciprocatory motion of the fluid handling mechanism into rotary motion of the shaft or vice versa.

Another object is the provision of a rotary hydraulic motor wherein fluid under pressure acts 15 first on a set of reciprocating members, the movements of which are transferred to a driven shaft having rotary motion, by a new and improved transfer device loosely engageable with the reciprocating members and having a permanent variably tiltable connection with the driven shaft.

Still another object is the provision in a device of the character described of new and improved means for adjusting the conversion means 20 to vary the speed of the device when used as a motor or to vary the displacement of the device when used as a pump.

Still another object is the provision of a rotary hydraulic motor wherein fluid force is transferred from a set of reciprocating members to 30 a rotary drive shaft which provides a new and improved means for automatically varying the speed of the motor by adjustment of the means used to transfer the motion, accompanied by a manual adjustment for determining for a given occasion the maximum limit which cannot be exceeded by variation in the speed of the motor.

35 A further object is the provision of an automatically adjustable, variable speed, rotary hydraulic motor in which a manual adjustment is provided for determining the minimum limit below which the variable low speed of the motor will not be permitted to pass.

Still a further object is the provision of a 45 rotary hydraulic motor provided with means for converting reciprocatory motion into rotary motion, which is equipped with a manually operated adjusting means for varying the speed of the motor during operation.

50 Other objects and advantages will become apparent from the following detailed description taken in connection with the accompanying drawings, in which:

Fig. 1 is a longitudinal section of the preferred form of the invention.

Fig. 2 is a fragmentary longitudinal section showing the shaft and valve passages rotated 90° from the position of Fig. 1.

Fig. 3 is a section on the line 3—3 of Fig. 1, looking in the direction of the arrows.

Fig. 4 is a cross section taken on the line 4—4 of Fig. 1, looking in the direction of the arrows.

Fig. 5 is a partial section of a modification of the device showing an alternative control adjustment.

Fig. 6 is a modification of the device showing a partial section devoted to a manually operated adjusting mechanism.

While I have shown in the drawings and will herein describe in detail the preferred embodiment of my invention, it is to be understood that I do not thereby intend to limit the invention to the specific form disclosed, but aim to cover all modifications and alternative constructions falling within the spirit and scope of the invention as expressed in the appended claims.

It is further to be understood that although the operation of the invention has been described as that of a variable speed, reversible motor, all of the parts, nevertheless, may be used in the same relation but with the application of power reversed in order to convert it into a fluid pump.

The motor herein described contemplates the utilization of a fluid under pressure, such as oil, for example, as a driving medium in order to produce in the motor a vibrationless rotary motion accompanied by a considerable reserve of power. In the embodiment shown, the motor operates first to transform the motive power supplied by the hydraulic fluid into reciprocatory motion and then convert this motion by novel communicating or transfer means into motion which rotates a drive shaft. In order that the speed of the motor may be changed as desired, an adjustment is provided for the communicating means which can be operated by fluid pressure from an auxiliary circuit if preferred and which, depending upon the operative needs of the mechanism, may be additionally provided with a limiting device for adjustably determining either the maximum or minimum speeds at which the motor may operate.

Hydraulic fluid is supplied to the motor through an intake port from which it is conducted through a rotating valve member formed in the drive shaft to a series of cylinders containing reciprocating pistons from which, after its energy has been utilized, the fluid is returned through the same valve member to an exhaust port. Motion thus imparted to the pistons is taken up by a wobble

plate and transformed into rotary motion to rotate a drive shaft. In order to change the speed of the motor a leverage system, shown herein as a wedge and pin device, is used to change the rate of transformation of motion by changing the tilt of the wobble plate. The wedge may be operated either automatically by fluid pressure and a spring, or manually, a special stop being provided with the automatic adjustment to provide a selected maximum or minimum speed adjustment of the motor above or below which the motor cannot be operated.

There is provided for the invention a casing generally designated 10 for housing the various parts of the motor, which consists of several portions including a body 11, a cap 12 forming one end of the casing, and an end plate 13 forming the other end. Rotating within the casing is a shaft 14 suitably journaled in a central bore thereof forming the drive shaft and in turn driven through the novel transfer means. Hydraulic fluid enters an intake passage 15 for operation of the motor in one direction, from which it is conducted to a reciprocating power mechanism designated generally 16. The reciprocating power initially produced is transferred from the mechanism 16 by means of a wobble plate 17 to the shaft 14. Adjacent the inside end of the shaft there is an automatic adjusting mechanism indicated generally at 18, and a manually operated device designated generally 19 for controlling or limiting the action of the automatic mechanism. Tapped holes 9 are provided in the body 11 to secure it to a support.

The body 11 has a longitudinal stepped bore having tubular portions 22 and 23 and a wide recessed portion 24 at the end, all within the casing 10. At the end of the body adjacent the recess 24 the cap 12 is secured in place by bolts 10 or other suitable means, and at the opposite extremity the end plate 13 is similarly secured. Within the body are a plurality of longitudinally disposed and annularly arranged cylindrical chambers or pockets 25 slightly narrowed in cross section at the points 26 and having a plug 27 for closing one end. The open ends of the cylindrical chambers communicate with the recessed portion 24 of the body 11. Herein the motor has seven cylinders, shown in Figs. 3 and 50 4, each communicating as indicated with the recess 24 at one end and having each a radial duct 28 communicating with the smallest portion 22 of the central stepped bore. These ducts 28 may be formed by a drilling operation after which the outer end of the duct is closed by means of a plug 29. Also formed in the body 11 are two ports, one previously designated as the intake port 15 for the hydraulic fluid, and the other here designated as 30 for exhaust of the fluid, for operation of the motor in a given direction. Each of the ports communicates with the bore 22 by means of passages 31 and 32, respectively. In order to reduce the amount of material required for the casing, the body 11 may 60 conform on the exterior contour to the cylindrical pockets 25 (see Fig. 3) except for an annular flange adjacent the junctions of the body with the cap 12 and with the end plate 13.

Reciprocable in each of the cylindrical chambers 70 25 is a reciprocating member here taking the form of a piston 35 having a narrower, rounded end 35' projecting from the cylindrical chamber. These pistons have at all times a full bearing surface in the narrower portions 26 of 75 the cylindrical pocket and in order to reduce the

friction a portion 26' of the pocket is formed by an undercut intermediate its ends. A portion 25' adjacent the head of the piston, being larger in diameter than the piston, permits the end thereof to be entirely surrounded with fluid and thus reduces side thrust on the piston.

Extending longitudinally and centrally of the motor is the shaft 14 which projects at the left through the end plate 13, and which is journaled at the opposite or right hand end within 10 the cap 12. Adjacent the projecting end there is a rotary bearing 36, located within the end plate, and a packing 37 for sealing the central aperture of the end plate within which the shaft 14 rotates. A rotary step bearing 38 provides the 15 means for journaling the opposite end of the shaft 14, the inner portion of the ring being secured to the shaft by means of a retaining ring 39 and by an abutting engagement with a shoulder 40 formed upon the shaft itself. A conventional pair of retaining rings maintain the ball bearings 42 in position within the ring 38.

To impart rotary motion to the shaft 14, means is provided for transforming the reciprocatory movement of the pistons 35 into rotary movement of the shaft. Herein this means takes the form of the wobble plate 17 having an annular outer ring 45 in engagement with the ends 35' of the pistons 35 and an inner concentric ring 46 secured to the outer ring by means of a retainer 30 ring and bearings 48. The inner ring is pivotally secured to the drive shaft 14 by means of a pin 49 which pierces the drive shaft at a point slightly to one side of the central axis so that the mounting of the wobble plate is slightly eccentric. An inner cylindrical portion 50 of the inside ring of the wobble plate is retained in a given fixed and tilted contact with a curved bulge 51 of the drive shaft 14 by the combined action of the eccentrically positioned pin 49 and the 40 pistons 35.

As each successive piston 35 is moved progressively through its working stroke from left to right, it tends to tilt the adjacent contacting portion of the wobble plate outward toward the 45 right. Since, however, the plate as an entirety is permanently attached to the shaft 14, the tendency to tilt successive portions of the plate actually results in the particular high point of the plate being rotated, carrying with it the shaft 50 14 thereby forming a means of communicating motion to the shaft from the pistons. It should be noted, also, that the actual angle of the tilt of the wobble plate remains constant and fixed for a given speed of motor operation.

To reduce the number of rotary parts of the motor to a minimum and thereby facilitate operation of the speed changing mechanism at all speeds, the drive shaft 14 also functions as a valve controlling the supply and the exhaust of 60 fluid to and from the seven cylindrical chambers of the motor. To that end a portion of the shaft intermediate the protruding end and the wobble plate is suitably passaged to constitute a valve rotatable within the bore 22. The bore at this 65 point has formed therein the radial ducts 28 previously described and also annular internal and axially spaced grooves 55 and 56 communicating with the ports 15 and 30, respectively, through the respective passages 31 and 32. The 70 shaft 14 in turn is formed with annular grooves 57 and 58, respectively, complementary to the grooves 55 and 56 in the body 11. Intermediate the grooves 57 and 58 the shaft is formed with milled cuts 59 and 60 on diametrically opposite 75

sides of the shaft, as seen to good advantage in Fig. 2. The milled cut 59 communicates with the groove 57 by means of a pair of diagonal passages 61, while the cut 60 communicates with the groove 58 by means of a pair of diagonal passages 62.

The milled cuts 59 and 60 are disposed in the plane of the radial ducts 18 and, as best seen in Fig. 3, are each in communication thereby with three of the cylinders. The duct leading to the seventh cylinder is closed by a portion of the shaft intermediate the cuts 59 and 60. The three cylinders communicating with one of the cuts 59 in the present instance are receiving fluid while the three cylinders in communication with the remaining cut 60 are discharging fluid, though the contrary may be true for reverse operation. The piston in the seventh cylinder is on dead center at the lowest point on the wobble plate and has no movement whatsoever so that the duct leading therefrom may be closed. As above noted, the shaft 14 may be made to rotate in either direction depending upon whether operating fluid is supplied to the port 15 or the port 30.

For rotating the motor in a clockwise direction, as viewed from the right end, fluid enters at the intake port 15, passes through the passages 31, 61 and the cut 59 into the cylindrical chamber 25 by way of duct 28. After its energy is expended upon the piston 35 and the shaft 14 is sufficiently rotated, the fluid returns by way of ducts 28, the cut 60, and passages 62 and 32 to the exhaust port 30.

In order that the speed of the motor may be altered during operation, the adjusting mechanism 18 has been provided, whose function it is to vary the tilt of the wobble plate. A change in speed is accomplished by reason of the fact that when the angle of tilt of the wobble plate is decreased the pistons 35 reciprocate through a shorter distance. Less fluid is required to fill the unoccupied portion of the cylindrical chamber 25 and hence for fluid supplied at a given pressure and volume the movement of the pistons is much more rapid. Conversely, when the tilt of the wobble plate is relatively great, the reciprocating motion of the pistons 35 is correspondingly great, and since considerably more fluid is required to fill the lower portion of the cylindrical pocket in order to drive each piston to its maximum movement, a longer time is taken for this portion of the operation, which results in operation at a slower speed.

To vary the tilt of the wobble plate, leverage is applied by means of a shifting mechanism comprising in this instance a wedge device carried by the shaft. To accommodate the device the end of the drive shaft 14 adjacent the wobble plate has formed therein an axial passage 65 and has disposed at an angle to the axial passage a somewhat radially directed passage 66. Within the radial passage, a pin 67 is positioned which slides freely back and forth and contacts at one end a portion of the cylindrical interior 50 of the inside ring of the wobble plate. Extending within the axial passage 65 is a rod 68 which has a wedge shaped face 69 at the inside end positioned in sliding contact with the adjacent end of the pin 67. When the rod is extended inward, the wedge 69 tends to force the pin 67 outward and to change the tilt of the wobble plate to a flatter plane. As the rod 68 is withdrawn, the wobble plate, due partially to the unequal leverage produced by the eccentricity of its

mounting, is forced more into a tilted position driving the pin 67 back against the now adjacent narrower portion of the wedge shaped face 69 of the rod 68.

As provided herein, the rod, together with the pin, rotates with the drive shaft 14. Any connection therefore with the rod of a means to impart endwise motion to it will be a rotatable connection.

In the preferred form of the device shown in Fig. 1, an automatic means is provided for imparting this endwise motion to the rod in order to change the speed of the motor. This automatic means comprises a cylindrical chamber 10 formed within the cap 12 having slidably positioned therein a piston head 11. The rod 68 previously referred to is swivelly connected to the piston head 11 by means of a roller bearing 12 secured therein by a threaded ring 13. The piston head is so positioned within the cylindrical chamber 10 that it divides the space into two compartments, one 14 on the left or inner side, the other 15 at the outside end. Located within the compartment 14 is a pressure element shown herein as comprising a helically coiled spring 16 supported on a ring 17 at one end and bearing against the piston head 11 at the other end so that its tendency is to force the piston head outward, thereby to withdraw the rod 68 and permit the wobble plate to occupy a position wherein it is tilted a maximum amount, which is the position for low speed of the motor. A drain port 19 communicates with the compartment 14 for conducting back to a supply tank any quantity of fluid which may collect there due to leakage past the pistons.

The compartment 15 is sealed and has a threaded port 18 for connection with a source of auxiliary fluid under pressure. This source may be the main fluid supply when the mechanism is operating as a motor or may be an auxiliary supply. When fluid is admitted through the port 18 into the compartment 15, the pressure tends to force the piston head 11 inward toward the left and overcome the force of the spring 16. Motion of the piston head in this direction tends to flatten the tilt of the wobble plate and thereby to increase the speed of the motor.

There is additionally provided the manually operated limiting device 19 for limiting the low or minimum limit below which variations in low speed of the device are not permitted to take place. To perform this function, a pin 80 is secured in the cap 12 by means of an adjusting collar 81 to which the pin is non-rotatably fixed by means of a nut 82. The pin has a head 83 located within the compartment 15 where it may be brought into contact with the adjacent face of the piston head 11. Mounted upon said face of the piston is a guide sleeve 84 which surrounds the head 83 of the pin.

The pin 80 is retained in the cap portion 12 of the casing within an aperture 85 and adjacent the aperture is a series of packing rings 86 clamped into position by a packing nut 87, in order to form a fluid-tight seal against leakage from the compartment 15.

By means of the structure just recited, there is provided an automatic pressure operated speed changer for the rotary hydraulic motor capable of transforming the force supplied by fluid at a constant volume into rotary motion variable with respect to speed and power. In addition, manual means is provided for limiting the low speed to which the motor will automatically be reduced.

upon release of the applied pressure used in the first instance to determine the high speed of operation.

As an alternative arrangement, it is sometimes desirable to have an adjustable high speed limit for the motor. Mechanism for supplying the adjustment is shown in Fig. 5 and is designated generally 19'. The operation of this modified feature is to limit the extent of movement of a piston head 71' toward the left when under pressure, in order to control the application of the pressure when used to increase the motor speed.

For this purpose, the main portions of the device are essentially the same as shown in Fig. 1, except that a pin 80' is provided having a length slightly shorter than the pin 80 previously described. Also inside compartment 75' and attached to the piston head 71' is a modified form 20 84' of a guide sleeve. This particular form has a closed end portion 90 forming a shoulder 91 and a central aperture 92 through which the shank of the pin 80' extends. A head 83' of the pin 80' provides in this instance an annular abutment 93 at the inside edge. The pin is fixed to an adjustable collar 81' in the customary manner by a lock nut 82' and is sealed liquid-tight in the cap 12' by means of the customary packing 86' and packing ring 87'.

30 It will be noted in the position shown, which is the initial or lowest speed position for the motor, that the head 83' of the pin 80' clears the adjacent surface of the piston head 71' by a slight amount, permitting the end portion 90 of the guide sleeve 84' to abut the bottom face 94 of the compartment 75.

When it is desired to adjust the motor in order to limit the rate beyond which variations in high speed of the motor are not permitted to take 40 place, the adjusting collar 81' is screwed in or out in order to set the head 83' of the pin in a desired position. Then, when fluid under pressure is introduced through port 78' into the compartment 75', the piston head 71' is driven inward toward the left. At some point, depending upon the position of the head 83' of the pin, the shoulder 91 of the guide sleeve will come into contact with the abutment 93 of the pin and prevent the piston head from moving any further 45 toward the left. This in turn prevents the flattening of the tilt of the wobble plate beyond a certain amount, thereby determining the maximum speed of the motor. This adjustment can be made while the motor is running or when at 50 rest.

When the pressure is released, a spring 76' acting in a manner similar to the spring 76 of Fig. 1, immediately returns the piston head 71' to the position shown in Fig. 5, which is, as previously noted, the lowest speed position or the 55 position occupied at rest.

Attention is directed in this connection to the fact that for either the preferred form shown in Fig. 1, or the modified form of Fig. 3, fluid introduced under pressure into the compartment 75 is customarily an auxiliary supply of fluid. Furthermore, whenever the fluid is an auxiliary supply rather than from the main fluid lines, such a supply may be operated either manually through 60 a conventional type of valve (not shown) or automatically as, for example, by valves of the usual sort operated by dogs properly positioned on the moving elements of any machine with which the motor might be used.

75 Still another modification is shown in Fig. 6,

wherein the device is arranged to be adjusted by manual means only. The operating parts housed within the casing are substantially the same as described for Fig. 1, the essential difference being that the cap 12'' is somewhat modified in form. A manually operated adjustment of this sort can be used to change the speed at which the motor operates, either while the motor is at rest or while it is operating under a load.

As shown in Fig. 6, the head 12'' has a threaded aperture 100 at the outer end in which is inserted a threaded block 101. A rod 68'' constructed substantially in the form shown in Fig. 1 is journaled in the block 101 by means of a bearing ring 102 secured in place by a retaining ring 103. The block is shown provided with a shank 104 the end 105 of which is squared off to receive a wrench or crank. At the outside end of the aperture 100 a packing 106 is inserted in order to form a fluid-tight joint and a drain 107 is provided for conducting back to the supply tank any fluid which might leak into the space formed inside the cap by the aperture 100.

In order that whatever adjustment at which the device is set may remain constant, a frictionally operated locking means is provided. At one side of the aperture 100 is a small radially disposed passage 111 which opens into the aperture 100 at the threaded portion. In the bottom of the passage is positioned a shoe-like plug 108. The plug is positioned so that it bears directly upon the threaded exterior of the block 101. This plug is releasably held in place by means of a coiled spring 109 retained in position by a screw plug 110. The tension of the spring 109 can be increased or diminished a desired amount by screwing the plug 110 in or out.

It will be seen, therefore, from the drawings and the accompanying description, that there has been provided a rotary fluid motor of a very precise type which operates under a high starting torque and whose speed can be adjusted either manually or automatically by small increments of any desired amount and which, by such a fine control over adjustment, is adapted to work requiring the highest degree of precision.

I claim is my invention:

1. In a fluid handling mechanism having a casing, a drive shaft member journaled in the casing, a tiltable wobble plate associated with the shaft member, adjusting means for changing the tilt of the wobble plate comprising a pin slidably secured to the shaft having contact at an angle with the wobble plate at one end, a rod extendable longitudinally along the shaft having its one end shaped for progressive varying contact with the pin and its other end extending outward from the shaft, and means engaging the casing and said other end of the shaft having a swivel connection with one and a longitudinally shiftable connection with the other for shifting said rod endwise in order to change the position of the pin in contact therewith and thereby vary the tilt of the wobble plate.

2. In a fluid handling mechanism of the character described having, in combination, a casing, a shaft rotatably journaled in the casing, a pivotally mounted wobble plate, and means for adjusting the tilt of the wobble plate comprising a first element engaging the wobble plate, a pressure responsive device in the casing cooperable with the first element for adjusting the wobble plate between high and low limits of adjustment, manually actuatable limiting means cooperable with the device for selectively determining one

5 of the limits of adjustment comprising a rod extending slidably within the casing and a cap fixed to the projecting end of the rod and threaded onto the casing to effect longitudinal shift of the rod by rotation of the cap, sealing means between the rod and casing, and means on the pressure responsive device cooperating with the rod to determine one of the limits of adjustment.

10 3. In a fluid handling mechanism, a shaft, a wobble plate pivotally mounted on said shaft, and means for adjusting the tilt of the wobble plate comprising means slidably longitudinally of the shaft and having a beveled end providing a cam surface, and means interposed between said 15 wobble plate and the beveled end of said first mentioned means for adjusting the tilt of the wobble plate as the first mentioned means is shifted longitudinally of said shaft.

20 4. In a fluid handling mechanism, a shaft, an annular wobble plate surrounding said shaft and pivotally mounted thereon eccentrically of the shaft, and means for adjusting the tilt of the wobble plate comprising a pin slidably mounted in said shaft for movement generally radially of the shaft and at right angles to the journal on which said wobble plate is pivoted, a rod extending slidably within said shaft and having at its inner end a beveled surface, said pin at one end engaging said beveled surface and at the other 30 end engaging said wobble plate to change the tilt thereof as said rod is shifted longitudinally of the shaft, and means for shifting the rod longitudinally.

35 5. A fluid handling mechanism of the character described having, in combination, a drive shaft, a wobble plate carried by the shaft, and means for adjusting the wobble plate angularly on the shaft including an axial passage in one end of the shaft, an intersecting aperture in the 40 shaft disposed at an angle to the tilt of the wobble plate, means slidable in said passage and aperture having contact with the wobble plate at one end and projecting from the shaft at the other end, and means for moving said last mentioned means to adjust the angular position of the wobble plate on the shaft.

45 6. A fluid handling mechanism of the character described having, in combination, a drive shaft, a wobble plate carried by the shaft, a pivot pin 50 for the wobble plate extending transversely through the shaft eccentrically of the shaft axis, and means for adjusting the wobble plate angularly on the shaft including an axial passage in one end of the shaft, an intersecting aperture in the shaft disposed at an angle to the tilt of the

wobble plate, means slidable in said passage and aperture having contact with the wobble plate at one end, and projecting from the shaft at the other end and means for moving said last mentioned means to adjust the angular position of the wobble plate on the shaft. 5

7. A fluid handling mechanism of the character described having, in combination, a drive shaft, a wobble plate carried by the shaft and adjustable angularly thereon, a pivot pin for the wobble plate extending transversely through said shaft and eccentrically on one side of the shaft axis, and means for adjusting the wobble plate angularly on said pin comprising a device movably mounted on said shaft and having a portion 15 engaging the wobble plate on the other side of the shaft axis.

8. A fluid handling mechanism of the character described having, in combination, a drive shaft, a wobble plate carried by the shaft and adjustable angularly thereon, a pivot pin for the wobble plate extending transversely through said shaft and eccentrically of the shaft axis, and means for adjusting the wobble plate angularly on said pin. 20 25

9. A fluid handling mechanism having, in combination, a drive shaft, a tiltable wobble plate associated with the shaft, adjusting means for changing the tilt of the wobble plate comprising an axial passage at one end of the shaft and a 30 connecting aperture in the shaft disposed at an angle to the tilt of the wobble plate, a pin slidable in said aperture having contact with the wobble plate at one end and extending into the axial passage of the shaft at the other end, a rod extendable axially into the shaft having its one 35 end shaped for progressive varying contact with the other end of the pin and the other end extending outward from the shaft, and means for moving said rod relatively to the shaft for causing said one end to shift the pin and thereby proportionately vary the tilt of the wobble plate. 40 45

10. A fluid handling mechanism of the character described having, in combination, a drive shaft, a wobble plate carried by the shaft and adjustable angularly thereon, a pivot pin for the wobble plate extending transversely through said shaft and eccentrically on one side of the shaft axis, and means for adjusting the wobble plate angularly on said pin comprising a device movably mounted on said shaft and having a portion 50 engaging the wobble plate on the other side of the shaft axis and means including a piston for actuating said device. 55
